UNITED STATES PATENT OFFICE.

SAMUEL GILBERT DAMREN, OF AUBURN, MAINE.

EXTENSION-VALISE.

SPECIFICATION forming part of Letters Patent No. 351,745, dated November 2, 1886.

Application filed July 26, 1886. Serial No. 209,103. (No model.)

To all whom it may concern:

Be it known that I, SAMUEL GILBERT DAMREN, of Auburn, in the county of Androscoggin, of the State of Maine, have invented 5
a new and useful Improvement in Extension-Valises; and I do hereby declare the same to be described in the following specification and represented in the accompanying drawings, of which—

10 Figure 1 is a longitudinal section of a valise of my invention. Fig. 2 is a view of a sheet of card material, showing the lines on which it is cut and those on which it is bent at right angles in order to form it into one of 15 the separate half portions or boxes of the valise. Fig. 3 is a horizontal section, and Fig. 4 a vertical section, of one of the said boxes.

The nature of my invention is defined in the claims hereinafter presented, such invention being a new or improved manufacture, consisting of an extension-valise having each of 20 its two sections composed of a box of card-board or sheet material cut, bent, and folded in manner as hereinafter described.

25 In Figure 1, A and B denote the two sections or boxes composing the body and cover of the valise, the body part A extending, mouth upward, within the cover B, which has its mouth downward, as is usual with such valises. Each of the said sections is made like the other—that is, it is composed of a piece of card-board or sheet material cruciform in shape, as shown at *a e f g h b c m l k i d* in Fig. 2. It is cut through on the lines *e o, h p, s i, 30 t m*, and bent at a right angle on each of the dotted lines *o p, p t, t s, s o, n o, p q, r s, and t u*. In other words, each rectangular part *h b c m* and *a e i d* is first turned upward toward the other at a right angle to the rectangle 35 between them, after which each of the terminal rectangular portions *f g p o* and *k l t s* is turned upward at a right angle to the rectangular portion *o p t s*. Next, the rectangular parts *a e o n, b h p q, c m t u*, and *d i s r* are 40 also each turned at a right angle to the next adjacent part of the wing, and are folded, as shown, against the inner sides of the two end portions *f g p o* and *k l t s*. The rectangular 45

portions *f g w v* and *k l y x* may next be folded down upon the next adjacent edges and inner 50 sides of the rectangular parts *a e o n, b h p q, c m t u*, and *d i s r*.

The parts lapped on each other may be secured together by rivets, or by paste or cement suitably applied to them, the sheet by such 55 means being converted into an open box, which I usually cover externally and line internally with cloth or other proper material.

To the cover part a suitable handle and a closing or binding strap or straps for the two 60 parts are to be applied, as is usual with extension-valises.

From the above it will be seen that each box or section of the valise is composed of a sheet of material of which the rectangular 65 part E constitutes the bottom, the rectangular portions I and M the opposite sides, and the remaining rectangular portions H D L K F N unite to form the two ends, or do so with the rectangular laps C and G. 70

I therefore claim—

1. As an improved manufacture, an extension-valise having its body as well as its cover consisting of an open box, composed of a piece of sheet material cruciform in shape and cut 75 and folded, and having the parts folded on each other fastened together by cement or suitable means, so as to form the ends of the box, in manner as specified.

2. The valise cover or box, made of sheet 80 material, cruciform in shape, and cut, folded, and bent, and having the parts folded on each other secured together by cement or other proper means, substantially as described, the wing portions of the cross being bent at a right 85 angle to the intermediate portion, and also turned in and secured to end portions of the said intermediate portion, and parts of such intermediate portion being turned inwardly and lapped on and secured to the wings, as 90 represented.

SAMUEL GILBERT DAMREN.
